(57) **CLAIM**

The ornamental design for a wave sponge, as shown and described.

DESCRIPTION

FIG. 1 is a top perspective view of a wave sponge showing our new design;

FIG. 2 is a bottom perspective view of the wave sponge of FIG. 1;

FIG. 3 is a scraper end view of the wave sponge of FIG. 1; FIG. 4 is a soap pocket end view of the wave sponge of FIG. 1;

FIG. 5 is a bottom plan view of the wave sponge of FIG. 1; FIG. 6 is a top plan view of the wave sponge of FIG. 1; FIG. 7 is a side view of the wave sponge of FIG. 1; and, FIG. 8 is an alternate side view of the wave sponge of FIG. 1.

The broken lines in the drawings depict portions of the wave sponge that form no part of the claimed design.

1 Claim, 8 Drawing Sheets
